HANDLE FOR THE BOLT OF A RIFLE

William B. Ruger, Southport, Conn., assignor to Sturm,
Ruger & Co., Inc., Southport, Conn., a corporation of
Connecticut

Filed Apr. 4, 1969, Ser. No. 16,583

Term of patent 14 years

Int. Cl. D22—02

U.S. Cl. D22—7

FIG. 1 is a right side elevation of the handle for the bolt of a rifle showing my new design;

FIG. 2 is a top plan view of the bolt handle of FIG. 1;

FIG. 3 is a bottom plan view of the bolt handle of FIG. 1;

FIG. 4 is a rear elevation of the bolt handle of FIG. 1;

FIG. 5 is a front elevation of the bolt handle of FIG. 1;

FIG. 6 is a rear elevation of a slightly modified form of the bolt handle of the invention, the knob at the end of the bolt handle having a spherical rather than an ovoid configuration;

FIG. 7 is a right side elevation of the slightly modified bolt handle shown in FIG. 6;

FIG. 8 is a front elevation of the bolt handle of FIG. 6;

FIG. 9 is a top plan view of the bolt handle of FIG. 6 and;

FIG. 10 is a bottom plan view of the bolt handle of FIG. 6.

I claim:

The ornamental design for a handle for the bolt of a rifle, as shown and described.
